RUFFLE PRESS

Manuel Florea, Springfield, Ill., assignor to Louis C. Schmidt, Springfield, Ill.

Application February 19, 1937, Serial No. 126,661

2 Claims. (Cl. 223—57)

My invention relates to presses for laundry work and more especially to presses for work on ruffles to make them look natural after they have been washed in a laundry and dried; an object 5 being in my press to provide a means for pressing curtain ruffles and the like where it is desired to put such ruffles in the most natural and beautiful shape after the curtains have been cleaned and stretched.

10 A further purpose of my press is to provide an effective means of mechanically pressing curtain ruffles and other ruffles without pressing them by hand and without running the curtain and the like through a process that would be hard on the curtain.

15 A particular purpose of my ruffle press is to provide a machine by which the curtain ruffle or other ruffle may be pressed carefully and quickly and the operation not require anything of unusual skill in doing it and by which much time may be saved in doing such work.

20 I attain the objects of my machine by the press set forth in the annexed specification, recited in the claims and illustrated in the accompanying drawings in which like reference numerals indicate like parts in the several drawings.

25 Referring to the drawings:

30 Fig. 1 is a perspective of my ruffle press wherein in the molds shown are to be used in the pressing of a curtain ruffle.

35 Fig. 2 is a cross-sectional view of my press showing a curtain ruffle being held in place by the press while the press fingers are operating.

40 Fig. 3 is a cross-sectional view similar to Fig. 2 wherein there is shown an additional control of the press fingers.

45 Fig. 4 is an end view of my ruffle press when the press fingers are lifted and the machine is not in operation.

50 Fig. 5 is a perspective of one of the ruffles formed by my press.

Fig. 6 is a perspective of a larger ruffle formed 45 by larger molds than would be used for the ruffle shown in Fig. 5.

55 Fig. 7 is a perspective of some V shaped ruffles which will be used in some situations and which would require a suitable form of mold and pressing finger operating in connection with my press, such as is shown in Figure 11.

Fig. 8 is a perspective of a group of knife pleats for ruffles adapted to be formed by still a different form of mold and pressing finger (see Fig. 12) 50 operating in connection with my machine.

Fig. 9 is a rear view of my ruffle press disclosing details of the mechanical structure thereof.

Fig. 10 is a perspective of one of the pressing fingers used for forming the ruffles shown in Fig. 5 and Fig. 6.

Fig. 11 is a detail of one of the pressing fingers illustrated for pressing one of the V shaped ruffles as shown in Fig. 7.

Fig. 12 is a detail of a pressing finger adapted to be used on my device for pressing knife pleats 10 as shown in Fig. 8.

Referring in more detail to the preferred construction of my ruffle press and to its operation, I have developed a practical and economical device wherein I provide a series of uniformly 15 spaced molds 1 set at desired spaces apart and heated by any suitable heat medium, which in this case I have chosen to be an electric heating coil 2 to avoid too much machinery to be handled.

These molds may be made of any desired design 20 and placed closer together or farther apart as the need may require on different ruffles of different design.

However, in the drawings the molds are designed as shown for curtain ruffles and are relatively larger than a mold for a small ruffle would be.

In the operation of my press therefore as a curtain ruffle press in this instance, I provide a series of molds 1 aligned either in a straight line 30 along a shelf 2 as shown in Fig. 1 or in a curved line or other desired arrangement of molds.

The operator places the curtain ruffle 3 for instance on the press, as shown in Fig. 1 (the curtain ruffle only is shown in this figure), with 35 the ruffle spread out over the molds 1 as shown so that the binding edge 4 will lay snugly up close to the molds on shelf 2.

He then pushes down on foot pedal 5 to pivotally swing the top portion 6 over into operative 40 position over the ruffle mold 1 so that bar 7 will hold binding edge 4 tightly down.

While bar 7 is holding binding edge 4 of the curtain in place so that the curtain ruffle 3 may be pressed then the finger presses 8 which are 45 arranged in parallel spaced relation are at the same time lowered in between the molds to press the curtain ruffle 3 between molds 1; thus these fingers hold the curtain ruffle snugly down over the molds.

50 Thus when the top portion 6 is pivotally moved down to permit fingers 8 to press down on ruffle 3 and when the heat is applied to the molds and to the fingers 8 the curtain ruffle 3 will be heated and pressed into the form desired for it.

- In the meantime after fingers 8 will let down upon the ruffle the free end of the fingers may be forcefully but carefully placed harder against ruffle 3 by the operator merely by pushing on handle lever 11 in order to pivotally swing fingers 8 down more snugly against the ruffle. This movement forces the free end 12 of finger 8 more firmly against that portion of the ruffle lying between molds 1.
- On the other hand when it is desired to move the entire finger down against the ruffle as is shown at numeral 13 in Fig. 3 this movement may be made in the fingers by first pushing in on handle 14 as indicated by the arrow in Fig. 3 to release the pressure on bolt 15 and permit supporting bar 16 to slidably move down with its pivotal pin 17 in slot 18. After pushing in on member 14 releasing the pressure of lug 19 from bolt 15 the operator pushes on lever 11 to force the entire group of fingers 8 down into the position shown in Fig. 3.

When moving the fingers back in place again springs 20 and 21 will aid in the movement of fingers 8 to put them back into place.

- Fig. 2 shows fingers 8 in operative position before bar 14 is pushed in.

It will be noted that top portion 6 includes the electric heating coils, the frame 22, link 23, bar 14, the heater casing 9 and the pressing fingers 8; while this upper portion is supported in its operative position by brackets 24 and 25 pivotally secured to rod 26 and is controlled by foot pedal 5 in its pivotal operation which is adapted to make the adjustment in link 27 and crank arm 28 secured to rod 26 while all this is supported on frame 29 mounted upon a table 30 supported by brackets 31.

- It will be observed that handle 11 for the upper portion 6 of my press has a pivotal support bar 31 while bolts 32 are adapted to hold bar 14 in proper alignment in their guiding slots 33 for the adjustment of pressing fingers 8.

Springs 34 are adapted to lift pedal 5 when pressure is released therefrom as well as to pivotally move the upper portion 6 back up out of the way as shown in Fig. 1 following the pressing operation.

The heating coils 10 in casing 9 are connected with a source of electric energy through a wire 35. Molds 1 also have heat coils connected through wire 35 with a source of electric energy therefor.

While I would not wish to be limited in this invention to the construction of pressing fingers illustrated in Figs. 10, 11 and 12 for the formation of ruffles shown in Figs. 6, 7 and 8 respectively yet these drawings will suitably illustrate a form of pressing fingers in each case that will accomplish the purpose desired.

- It will be obvious to the experienced operator of pressing machines in a laundry that within the scope of my invention it will not be necessary to

be limited in the form of ruffle to be pressed thereby; since it is evident that any one of a number of forms of mold can be used as well as any desired pressing fingers on my machine.

I do not choose to be limited to the specific construction of ruffle press disclosed in this specification for the reason that it is evident that certain minor changes may be desired in the form of the pressing fingers or the form of the molds without departing from the spirit and scope of my invention.

Having thus described the nature of my invention and the method of operating the same, what I claim is:

1. A ruffle press comprising a machine frame, a plurality of pressing molds arranged in alignment in parallel spaced relation, a plurality of pressing fingers pivotally supported and pivotally adjusted and a hand lever for making said adjustments; said pressing fingers adapted to be operatively moved into the space between said molds, means for heating said pressing molds and said pressing fingers and foot control lever means for moving said pressing fingers into operative position, a marginal clamp for holding a curtain and the like along the edge of said molds when the ruffles thereof are being pressed and a shelf in front of said molds for supporting the adjacent portions of a curtain and the like while the ruffle thereof is being pressed.

2. As a new article of manufacture a ruffle press for pressing curtain ruffles and the like and comprising a press frame, a shelf thereon, a plurality of pressing molds arranged in spaced relation adjacent said shelf and means for heating said molds, a foot control lever, brackets and a plurality of pressing fingers operatively and pivotally supported thereby, said foot control lever for optionally moving said pressing fingers into operative position between said pressing molds for forming said ruffles into predetermined shapes of pleats, a hand lever operatively and controllably connected with said pressing fingers for the adjustment and manipulation thereof after they have been moved into a position adjacent their operative position between said molds by said foot lever, a marginal clamp operatively mounted with said pressing fingers and adapted to be moved into operative position by said foot lever for holding a curtain and the like while the ruffles thereof are being pressed, electric coil means operatively connected with said pressing fingers for heating the same, a lever for manipulating said pressing fingers pivotally and means for optionally adjusting the position of said fingers and spring means connected with said foot lever and said hand lever for automatically retracting said pressing fingers and their mounting when released by the foot on said foot lever or by hand by said hand lever.

MANUEL FLOREA.
